UNITED STATES PATENT OFFICE

SADIE O'NEIL, OF SEATTLE, WASHINGTON

DESIGN FOR A BUILDING

Application filed October 7, 1931. Serial No. 41,333. Term of patent 3½ years.

To all whom it may concern:

Be it known that I, SADIE O'NEIL, a citizen of the United States, residing at Seattle, in the county of King and State of Washington, have invented, a new, original, and ornamental Design for a Building, of which the following is a specification, reference being had to the accompanying drawings, forming part thereof.

I claim:

The ornamental design for a building, as shown.

SADIE O'NEIL.
